UNITED STATES PATENT OFFICE.

ORVAL L. SIMPSON, OF LAPAZ, INDIANA.

MEANS FOR RESUPPLYING AIR TO WATER-DISTRIBUTING SYSTEMS.

Application filed December 21, 1926. Serial No. 156,165.

This invention relates to water supplying and distributing systems in which the water from a well, cistern or other source is pumped into a tank by an electrically operated pump and delivered from said tank by air pressure when an outlet in the service pipe is opened. It is well known that the air pressure diminishes and is maintained by supplying air to replace that which is lost usually by passing off with the water when drawn from the tank.

In accordance with the present invention an air pipe is connected with the water pipe through which the water is pumped into the tank. A valve controls the admission of air to the air pipe and is normally held closed; however, when the air pressure within the tank is reduced the level of the water therein rises and through a float closes a circuit which effects a release of the said air valve, thereby permitting air being pumped into the tank along with the water being supplied thereto.

While the drawings illustrate a preferred embodiment of the invention it is to be understood that in adapting the means to meet specific needs and requirements the design may be varied and such other changes in the minor details of construction may be resorted to within the scope of the invention as claimed, without departing from the spirit thereof.

For a full understanding of the invention and the merits thereof, reference is to be had to the following description and the drawings hereto attached, in which,

Figure 1 is a schematic view illustrative of an embodiment of the invention.

Figure 2 is a sectional detail of a portion of the valve stem and associated parts on a larger scale.

Figure 3 is a sectional detail of the circuit closing means and coacting parts on an enlarged scale.

The numeral 1 designates a tank for holding a quantity of water of a distributing system for dwellings and 2 designates a pipe whereby water is supplied to the tank 1 from a suitable source by means of a pump, preferably electrically operated. An air pipe 3 is coupled to the water pipe 2 and 4 designates a valve for controlling the supply of air to the pipe 3. Under normal conditions the valve 4 is closed and is held shut by means of a lock device 5 which engages the lower end of a sleeve 6^a mounted

on the stem 6 of the valve 4. The sleeve 6^a is threaded on the stem 6 and is held in the required adjusted position by means of a nut 6^b on the upper end of the stem 6. The 60 stem 6 and sleeve 6^a are mounted in a guide tube 6^c applied to parts of a frame 9 which is slotted in a side at 6^d to receive the end of the lock 5. A spring 7 functions to normally hold the valve 4 closed. A flanged 65 collar 8 is threaded into a portion of the frame 9 and is formed with a seat against which the valve 4 closes by an upward movement. The lock device 5 consists of a bolt which is inclined upwardly at its active end 70 so as to automatically compensate for any wear between the valve 4 and its seat, whereby to secure the valve when seated. The lock bolt 5 is pivoted at one end to an enlargement of a lever 10 to which is fitted an armature 11 to be attracted by the core of an electro-magnet 12 when the latter is energized. The electro-magnet 12 is adjustable vertically by means of a screw 13 mounted in an upper cross-piece of the frame 9 and 75 having screw thread connection with the electro-magnet. A spring 14 mounted upon the screw 13 exerts a downward pressure upon the electro-magnet 12 and holds the same at its lowest position when the screw 80 13 is backed.

The frame 9 is coupled by means of a union 15 to a short length of pipe 16 threaded into the top of the tank 1, and its lower end has a depending neck portion in which 85 is formed an opening to register with the opening of the pipe 16. A plug 17 of insulating material is secured within the upper contracted portion of an opening 18 formed in the lower portion of the frame 9. The 90 plug 17 is retained in place by means of a hollow nut 19, the hollow side of the nut facing the plug, and receiving contacts 20 which are fitted to said plug. A hollow contact 21 is provided to co-operate with the contacts 20 and is loosely mounted in the nut 19, and receives the upper end of a stem 24 which is loosely mounted in a guide 22 secured within the lower end of the short 95 length of pipe 16. The contact 21 telescopes the upper end of the stem 24 and its upper end is of conical form and is adapted to pass between the contacts 20 and make electrical connection therewith, whereby to close the circuit including the electro-magnet 12, which, when energized, attracts the armature 11 and moves the lever 10 to with- 100 105 110

draw the lock 5 from the stem of the valve 4, which opens on the next suction stroke of the pump to supply air to the pipe 3 to be forced into the tank 1 along with the water 5 pumped therein. The stem comprises an outer section 24 and an inner section 25, the two sections having a screw-thread connection to admit of lengthening and shortening of the stem. A stop collar 26 threaded up- 10 on the outer section 24 limits the downward movement of the stem and contact 21 by engaging the guide 22.

The guide 22 consists of a plate which is confined between an inner shoulder of the 15 pipe 16 and the end of a guard 27 threaded into the lower end of the pipe 16. The guard 27 consists of a shell which extends into the tank 1 some distance below the pre-determined level of the water therein. A 20 float 28 is disposed within the guard 27 and is free to move vertically therein with the change of level of the water within the tank. Slots 29 are formed in the side of the upper portion of the guard 27 for the free ingress 25 and egress of air. The float 28 is connected to the lower end of the section 25 of the adjustable stem, and as the float moves up and down the contact 21 receives a corresponding movement and when the air pressure 30 within the tank decreases, the level of the water rises and the float 28 correspondingly moves upwardly, thereby bringing the contact 21 into engagement with the contacts 20, whereby to close the circuit through 35 the winding of the electro-magnet 12 which, becoming energized, attracts the armature 11 and releases the valve 4, which automatically opens on the suction stroke of the pump to admit air into the pipe 3, the air 40 thus drawn into the pipe 2 with the water being forced into the tank and replacing the air withdrawn and restoring the pressure. As the air pressure increases within the tank 1 the level of the water lowers, thereby permitting 45 the float 28 to descend and withdrawing the contact 21 from engagement with the contacts 20 and breaking the circuit through the electro-magnet 12. When the electro-magnet becomes de-energized the 50 armature 11 is released and the long arm of the lever 10 is drawn downward by means of a spring 30, the tension of which is regulated by means of a screw 31 in a manner well understood. A screw 32 threaded into 55 a portion of the frame 9 limits the upward movement of the long arm of the lever 10, thereby preventing contact between the armature and the core of the electro-magnet which is essential to prevent the sticking 60 thereof. A housing 33 encloses the frame 9, it being understood that provision is had for admission of air to be drawn into the pipe 3 when the valve 4 is unseated. The guard 27 prevents any waves of the water within 65 the tank 1 from affecting the float 28. The

spring 23 between the contact 21 and the float stem 24 admits of a positive connection between the contacts and obviates an intermittent make and break of the circuit by any fluctuations of the float due to undulations of the water within the tank. The spring 23 forms a positive connection between the parts 21 and 24 to cause the contact 21 to move downwardly with the stem 24 and clear the contacts 20. Jamb nuts 34 mounted on the stem 6 provide for maintaining the tension of the spring 9 which holds the valve 4 seated.

The service pipe is designated generally by the numeral 35 and is connected to the tank 1 at a determinate point below the level of the water therein, so that when an outlet is opened water will flow therefrom by reason of the pressure exerted upon the water by the air confined in the upper portion of the tank. The pipe 2 connected with the source of water supply is provided with a valve 36 to retain the water elevated by the pump and prevent loss from the tank 1. A pipe 37 connects the pipe 2 with the tank 1. Under normal conditions, that is, when the level of the water in the tank 1 is at a pre-determined point, operation of the pump simply supplied water to replace that drawn from the tank 1. However, when the level of the water in the tank 1 rises, due to loss of air in the upper portion of the tank, the float 28 ascends, closes the circuit through the electromagnet 12 and effects a release of the valve 4, so that on the next and succeeding suction strikes of the pump both air and water are drawn into the pipe 2 and are forced therefrom into the pipe 37 and tank 1 on the compression stroke of the pump. As the level of the water in the tank 1 lowers the float 28 descends, thereby breaking the circuit through the electromagnet and releasing the lock 5 which comes into play to prevent opening of the air valve 4. In consequence water only is pumped into the tank 1 to supply that drawn therefrom.

Having thus described the invention, I claim:

1. In a water distributing system, the combination of a pressure tank, a pump, a pipe for supplying water to the tank, an air pipe connected with the water supplying pipe, a valve for controlling the supply of air to the system and adapted to unseat automatically upon the suction stroke of the pump, a lock for holding the said valve seated under normal conditions, and means for automatically releasing the said valve and actuated by a rise of the level of the water in the pressure tank, due to a loss of pressure, which is automatically restored with the water supplied to the tank.

2. In a water distributing system, the combination with a pressure tank, a pump, a pipe for supplying water to the tank, and

an air pipe connected with the water supplying pipe, of a valve for controlling the supply of air to the system, and adapted to open automatically on the suction stroke of the 5 pump, locking means for normally holding the air valve seated, electrically operated means for releasing the said lock means, and float controlled circuit closing means adapted to be actuated by the change of level of 10 the water in the tank due to a diminished pressure.

3. In a water distributing system, the combination with a pressure tank, a water supplying pipe, an air pipe connected with the 15 water supplying pipe, and a valve for controlling the supply of air to the system, of a lock bolt for holding the air valve seated under normal conditions and movable in a path at an upward and outward inclination 20 to the path of movement of the air valve, electrically operated means for releasing the lock bolt, and float controlled circuit closing means adapted to be actuated by the change of level of the water within the pressure 25 tank.

4. In a water distributing system, the combination with a pressure tank, a water supplying pipe, an air pipe connected thereto and a valve for controlling the supply of air 30 to the system, of locking means for normally holding the valve seated, electrically oper-

ated means for releasing the lock means, spaced contacts included in the circuit, a movable contact for closing the circuit, a float actuated by the change of level of the 35 water within the pressure tank, and connecting means between the float and the movable contact including a yieldable element to admit of the circuit being maintained in closed position and not affected by any fluctuations 40 of the float.

5. The combination with the pressure of a water distributing system, a water supplying pipe, an air pipe connected to the water supplying pipe, and a valve for controlling the 45 supply of air to the system, of an adjustable stem for the valve, a lock bolt adapted to engage the said stem and normally hold the air valve seated, electrically operated means for releasing the lock bolt, fixed contacts in 50 the circuit of the electrically operated means, a movable contact, an adjustable stem having the movable contact yieldably connected thereto, a float connected to the stem of the movable contact and adapted to be actuated 55 by the change of level of the water within the pressure tank, and a guard receiving said float to prevent interference therewith by any wave motion of the water within the pressure tank.

In testimony whereof I affix my signature.

ORVAL L. SIMPSON. [L. s.]
